US00D628696S

(12) **United States Design Patent**
Robertson

(10) **Patent No.:** **US D628,696 S**
(45) **Date of Patent:** **** Dec. 7, 2010**

(54) **HANDLE**

(75) Inventor: **Brice Robertson**, Rancho Santa Margarita, CA (US)

(73) Assignee: **Ossur HF**, Reykjavik (IS)

(**) Term: **14 Years**

(21) Appl. No.: **29/342,640**

(22) Filed: **Aug. 28, 2009**

(51) **LOC (9) Cl.** **24-02**

(52) **U.S. Cl.** **D24/147; D8/352**

(58) **Field of Classification Search** **D24/133, D24/155, 188, 190, 147; 602/25, 20, 19, 602/35, 40; 24/714.6, 713.9, 715.1, 129 R; 128/99.1, 102.1, 101.1, 109.1, 876; D8/107, D8/94, 300, 310, 333, 349, 351, 352, 360**

See application file for complete search history.

(57) **CLAIM**

The ornamental design for a handle, as shown and described.

DESCRIPTION

FIG. 1 is a top perspective view of a handle, showing my design.

FIG. 2 is a rear perspective view of the handle of FIG. 1.

FIG. 3 is a top plan view of the handle of FIG. 1.

FIG. 4 is a bottom plan view of the handle of FIG. 1.

FIG. 5 is a front elevational view of the handle of FIG. 1.

FIG. 6 is a rear elevational view of the handle of FIG. 1; and, FIG. 7 is a side elevational view of the handle of FIG. 1, the other side elevational view is the same.

The broken lines immediately adjacent to the shaded areas represent the bounds of the claimed design while all other broken line showing portion of a handle is included for the purpose of illustrating environmental structure and forms no part of the claimed design.

1 Claim, 6 Drawing Sheets
